UNITED STATES PATENT OFFICE.

HORATIO N. FRASER, OF NEW YORK, N. Y.

DESIGN FOR A POCKET-BOTTLE.

SPECIFICATION forming part of Design No. 21,728, dated July 19, 1892.

Application filed May 26, 1892. Serial No. 434,501. Term of patent 14 years.

To all whom it may concern:

Be it known that I, HORATIO N. FRASER, a citizen of the United States, residing in the city, county, and State of New York, have invented and produced a new and original Design for a Pocket-Bottle, of which the following is a specification.

This invention relates to a new pocket-bottle, the principal feature of invention being a bottle having flat faces *a*, that are connected by rounded sides *b*, and a rib or welt surrounding its narrow sides and bottom, as hereinafter more clearly shown.

In the drawings forming part hereof, Figure 1 is a side view of my new design for a pocket-bottle. Fig. 2 is a horizontal section of the same on the line 2 2, Fig. 1; and Fig. 3 is a bottom view of the same.

The body *A* of the pocket-bottle has substantially flat faces *a*, that are connected by rounded narrow sides *b*. Looked at from the face the body of the pocket-bottle appears to be oval with flattened bottom. Extending around this bottle and projecting from the narrow sides *b* is a substantially continuous welt or rib *d*, which beneath the flat bottom of the pocket-bottle is spread out, as at *e* in Fig. 3.

What I claim, and desire to secure by Letters Patent, is—

The design for a pocket-bottle, substantially as shown.

HORATIO N. FRASER.
